Primary Examiner — Ian Simmons*Assistant Examiner* — Charles Hanson(74) *Attorney, Agent, or Firm* — Snell & Wilmer L.L.P.(57) **CLAIM**

The ornamental design for a combined wheelchair cover with a pouch, urinary pouch, arm pads, and backpack, as shown and described.

DESCRIPTION

FIG. 1 is a perspective view of a combined wheelchair cover with a pouch, urinary pouch, arm pads, and backpack, showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof.

The broken line showing is included for the purpose of illustrating environment and forms no part of the claimed design.
